ABSTRACT OF THE DISCLOSURE

Insecticidal, miticidal and nematocidal compositions containing as the active ingredient 3-phosphorylthio acrylamides of the general formula

This application is a continuation-in-part of U.S. Ser. No. 22,660, filed Mar. 25, 1970, now abandoned, which in turn is a continuation-in-part of U.S. Ser. No. 807,445, filed Mar. 14, 1969, now abandoned. This invention is concerned with 3-phosphorylthio acrylamides of the general formula

wherein

R¹ and R² are individually selected from the group RO or RS wherein R is alkyl or haloalkyl of 1 to 5 carbon atoms or alkenyl of 3 to 5 carbon atoms or the group R'R''N wherein R' and R'' are individually selected from alkyl groups of 1 to 5 carbon atoms;

R⁴ is hydrogen, halogen or alkyl of 1 to 5 carbon atoms; R⁵ and R⁶ are individually selected from

- (a) hydrogen,
- (b) alkyl of 1 to 12 carbon atoms,
- (c) alkyl of 1 to 12 carbon atoms substituted with halogen, cyano, hydroxy, alkoxy, alkylthio, carboalkoxy groups of 1 to 5 carbon atoms, phenyl morpholinyl, anilino or anilino substituted with halogen or nitro,
- (d) alkenyl of 3 to 12 carbon atoms,
- (e) alkynyl of 3 to 12 carbon atoms,
- (f) cycloalkyl of 3 to 6 carbon atoms,
- (g) phenyl,
- (h) phenyl substituted with halogen, alkyl of 1 to 5 carbon atoms, nitro or alkyl sulfonyl wherein the alkyl group is 1 to 5 carbon atoms,
- (i) benzyl,
- (j) benzyl substituted with halogen, alkyl of 1 to 5 carbon atoms or nitro,
- (k) alkoxy of 1 to 5 carbon atoms,
- (l) the carbamyl group —C(X)NHR⁷, wherein X is oxygen or sulfur, and R⁷ is alkyl of 1 to 12 carbon atoms,
- (m) the —C(O)R⁸ group wherein R⁸ is hydrogen, alkyl of 1 to 5 carbon atoms, alkyl of 1 to 5 carbon atoms substituted with a halogen, phenyl or alkoxy

2

of 1 to 5 carbon atoms, with the proviso that only one of R⁵ or R⁶ can be an alkoxy, the

or the —C(O)R⁸ group, and

(n) R⁵ and R⁶ taken together with the nitrogen to which they are attached are the pyrrolidinyl, piperidino, morpholino, or the thiomorpholino group.

It is understood that all the hydrocarbyl groups defined above may be straight-chained or branched.

These compounds exist as geometrical isomers and can or the *trans* form

or the *trans* form

or mixtures of these. The compounds where R¹ and R² are alkoxy and the *cis* stereoisomers are preferred as insecticides and miticides.

Compounds having the structure of Formula I have not heretofore been reported in the literature. The most closely related commercial insecticides are known by the trademarked names Azodrin and Bidrin. Azodrin has the structure

and Bidrin the structure

45 Literature references on these structures include U.S. Pat. 2,802,855 and S. C. Lau, J. Ag. Food Chem., 14, 145 (1966). It is to be noted that for these structures the most insecticidally active forms are considered to be the *trans* isomers with respect to the phosphoryl and carbonyl groups.

50 Japanese patent publication 636/65 discloses insecticidal properties for the compound

55 The insecticidal properties of esters of the general formula

have been described in British Pat. 892,326 and U.S. Pat. 3,059,014. The insecticidal properties of enol phosphates of the structure

have been reviewed in Chemical Reviews, 61, 631 (1961).

was heated to 45° C. There was added dropwise 29.7 g. (0.22 mole) of sulfonyl chloride in one hour at about 45° C. The mixture was stirred 3 hours. The resulting solid was filtered off, washed with ethyl acetate and vacuum dried to give 15.2 g. of white crystalline solid. By infrared spectroscopy and NMR, this was shown to be 2,4-dimethyl-3-isothiazolone hydrochloride.

(b) Preparation of *cis* - 3 - diethoxyphosphorylthio-2-methyl-N-methylacrylamide.—To a slurry of 6.62 g. (0.04 mole) of 2,4-dimethyl-3-isothiazolone hydrochloride in 150 ml. of ethyl acetate was added dropwise 6.65 g. (0.04 mole) of triethyl phosphite in 10 ml. of ethyl acetate. There was a slight exotherm. The mixture was stirred 1.5 hours and was then filtered to remove a trace of insoluble material. The filtrate was concentrated on a rotary evaporator to give 10.9 g. of pale yellow oil. The infrared spectrum was consistent with the desired product and NMR confirmed the structure. The oil was crystallized from a mixture of 10 ml. of ethyl acetate and 20 ml. of ether to give 5.0 g. of colorless cubes melting at 52°-55° C.

EXAMPLE 20

Preparation of *cis*-3-diethoxyphosphorylthio-N-ethylacrylamide

To a slurry of 4.97 g. (0.03 mole) of 2-ethyl-3-isothiazolone hydrochloride in 150 ml. of ethyl acetate with stirring was added a solution of 4.98 g. (0.03 mole) of triethyl phosphite in 10 ml. of ethyl acetate dropwise in 20 minutes. A slight exotherm raised the temperature from 22° C. to 30° C. Stirring was continued for 1 hour to give a clear solution. The reaction mixture was concentrated *in vacuo* to give 8.3 g. of pale yellow crystalline solid. The product was recrystallized from ethyl acetate to give 5.3 g. (67% yield) of *cis*-3-diethoxyphosphorylthio-N-ethylacrylamide.

EXAMPLE 37

Preparation of *cis*-3-ethoxy(methoxy)phosphorylthio-N-cyclopropyl-acrylamide

(a) Preparation of dimethyl ethyl phosphite.—To 46 g. (1.0 mole) of absolute ethanol was added 0.5 g. of sodium metal and the mixture was stirred until the sodium dissolved. To this was added 124 g. (1.0 mole) of trimethyl phosphite. The solution was distilled slowly at a vapor temperature range of 64° to 69° C. as 40 g. of methanol (identified by NMR) was removed. The residue was distilled through a 20 inch 16-plate Oldershaw column to give a main fraction distilling at 68° to 72° C. at 85-89 mm. pressure. By vapor phase chromatography this was determined to be 98% dimethyl ethyl phosphite and 2% trimethyl phosphite.

(b) Reaction of dimethyl ethyl phosphite with 2-cyclopropyl-3-isothiazolone hydrochloride.—A slurry of 7.1 g. (0.04 mole) of 2-cyclopropyl-3-isothiazolone hydrochloride in 150 ml. of ethyl acetate was stirred and cooled in an ice bath as there was added dropwise in 10 minutes a solution of 5.8 g. (0.042 mole) of dimethyl ethyl phosphite in 10 ml. of ethyl acetate. The mixture was stirred one hour and a clear solution resulted. The reaction mixture was concentrated to give 11.0 g. of a pale green crystalline solid. This was recrystallized from 12 ml. of ethyl acetate to give 8.2 g. of pale green crystals identified as *cis*-3-ethoxy(methoxy)-phosphorylthio-N-cyclopropylacrylamide.

EXAMPLE 69

Preparation of *cis*-3-dimethoxyphosphorylthio-N-(methylcarbamoyl acrylamide)

In to a round bottom flask was placed 6.32 g. (0.04 mole) of 2-methylcarbamoyl - 3 - isothiazolone, 4.0 g. (0.04 mole) of concentrated hydrochloric acid and 200 ml. of ethyl acetate. The resulting slurry was stirred magnetically as there was added dropwise a solution of 4.96 g. (0.04 mole) of trimethyl phosphite in 10 ml. of ethyl

acetate. A slight exotherm resulted in a rise in temperature of 5° C. The reaction mixture was stirred two hours longer. A solid residue was filtered off and amounted to 2.8 g. which melted at 161°-164° C. The filtrate was concentrated to give a solid which after washing with ethyl acetate was 5 g. melting at 162°-163° C. The ethyl acetate washing was concentrated to give 1 g. of solid. By infrared spectra all three crops of solid were determined to be the same and NMR confirmed these to be *cis*-3-dimethoxyphosphorylthio - N - (methylcarbamoyl)-acrylamide.

EXAMPLE 73

Preparation of *cis*-3-ethoxy(ethylthio)phosphorylthio-N-ethylacrylamide

A slurry of 2-ethyl-3-isothiazolone hydrochloride, 6.6 g. (0.04 mole) in 150 ml. of ethyl acetate was charged to a 300 ml. round bottom flask. To this was added dropwise in about 15 minutes at room temperature and with stirring a solution of 8 g. (0.044 mole) of O,O,S-triethylthiophosphate in 20 ml. of ethyl acetate. The mixture was stirred 2 hours at room temperature and most of the solid had gone into solution. The reaction mixture was filtered to remove 0.7 g. of insoluble solid and the filtrate was concentrated to give 12.9 g. of yellow oil. The oil was purified by chromatographing on silica gel, first using an acetone-hexane solution followed by an acetone-pentane solution. There was isolated from the purified main fraction 4.3 g. of colorless oil. By NMR its structure was confirmed to be *cis*-3-[(ethoxy) (ethylthio) phosphorylthio] - N-ethylacrylamide.

EXAMPLE 74

Preparation of *cis*-3-dimethylamido(methoxy)phosphorylthio-N-ethylacrylamide

To a slurry of 3.3 g. (0.02 mole) of 2-ethyl-3-isothiazolone hydrochloride in 75 ml. of ethyl acetate was added in 15 minutes at room temperature a solution of 2.74 g. (0.02 mole) of dimethyl N,N-dimethylphosphoramidite in 10 ml. of ethyl acetate. The reaction mixture was stirred 2 hrs. at room temperature, filtered to remove a slight amount of solid and the filtrate concentrated to give 5 g. of a red oil. The oil was purified by chromatographing an acetone-hexane solution on silica gel. The major fraction was concentrated to give 4 g. of pale yellow oil. By analysis and NMR this was found to be *cis*-3-[(dimethylamido) (methoxy) phosphorylthio] - N - ethylacrylamide of about 90% purity.

EXAMPLE 75

Preparation of *cis*-3-dimethoxyphosphorylthio-N-formylacrylamide

To a slurry of 2-formyl-3-isothiazolone (5.16 g., 0.04 mole) and concentrated hydrochloric acid (4 g., 0.04 mole) in 200 ml. of ethyl acetate was added dropwise trimethyl phosphite (4.96 g., 0.04 mole) in 10 ml. of ethyl acetate. There was a slight exotherm. The mixture was stirred 1 hour and was then filtered to remove insoluble impurities. The filtrate was concentrated to give an oil-solid mixture which was taken up in ethyl acetate. After standing overnight at 0° C. there was obtained 1.3 g. of a crystalline solid melting at 104-106° C. This is a 13% yield of *cis*-3 - dimethoxyphosphorylthio-N-formylacrylamide.

EXAMPLE 91

Preparation of *trans*-3-diethoxyphosphorylthio-2-bromo-N-ethyl-acrylamide

(a) Preparation of 3-diethoxyphosphorylthio-2,3-dibromo-N-ethylpropionamide.—A solution of 2.67 g. (0.01 mole) of *cis*-3-diethoxyphosphorylthio-N-ethylacrylamide in 50 ml. of chloroform was cooled to 0° C. To this was added dropwise 1.6 g. (0.01 mole) of bromine in 10 ml. of

chloroform. The solution slowly decolorized. After stirring overnight at room temperature, the reaction mixture was concentrated to give 4.3 g. of solid melting at 64°–67° C. This was a 100% yield of 3-diethoxyphosphorylthio-2,3-dibromo-N-ethylpropionamide. Its structure was confirmed by infrared and NMR spectra.

(b) Preparation of *trans*-3 - diethoxyphosphorylthio-2-bromo-N-ethylacrylamide.—To 8.6 g. (0.02 mole) of 3-diethoxyphosphorylthio - 2,3 - dibromo-N-ethylpropionamide in 100 ml. of acetone was added 2.0 g. (0.02 mole) of triethylamine in 10 ml. of acetone. After stirring for 2 hours NMR showed the reaction to be 68% complete. Another portion of 0.7 g. (0.007 mole) of triethylamine was added and the reaction mixture stirred overnight. The reaction mixture was filtered to remove 3.3 g. of triethylamine hydrobromide. The filtrate was concentrated to give to 5.4 g. of yellow-brown oil. By NMR this was shown to be *trans*-3 - diethoxyphosphorylthio-2-bromo-N-ethylacrylamide having a one proton vinyl doublet at 8.1

p.p.m. The corresponding *cis* isomer had a one proton vinyl doublet at 7.3 p.p.m.

EXAMPLE 92

Preparation of *cis*-3-dimethoxyphosphorylthio-N,N-dimethylacrylamide

To a solution of 4.85 g. (0.05 mole) of N,N-dimethylpropiolamide in 25 ml. of acetonitrile was added 7.8 g. (0.55 mole) of O,O-dimethylthiophosphoric acid. The solution was refluxed for 3 hours. The solvent was removed, the residue taken up in 150 ml. of chloroform, washed twice with 25 ml. portions of water, dried and concentrated under high vacuum to give 7.5 g. of a red oil. An ethyl acetate solution of this was chromatographed on 40 g. of silica gel to give 6.9 g. of light yellow oil. This was crystallized from a mixture of 5 ml. of ethyl acetate and 10 ml. of ether to give 3.2 g. of crystals melting at 41°–43° C. By NMR this was shown to be *cis*-3-dimethoxyphosphorylthio-N,N-dimethylacrylamide.

75

The novel 3-phosphorylthio acrylamides of this invention are biologically active. In particular they are effective as insecticides, miticides, nematocides and ovicides and as such exhibit a broad spectrum of activity. The *cis*-form (Formula II) is in general more active than its *trans*-isomer (Formula III).

Initial evaluations were made on the following mite, insects and nematode:

Code symbol	Common name	Latin name
TSM	Two-spotted spider mite	<i>Tetranychus urticae</i>
GPA	Green peach aphid	<i>Myzus persicae</i>
PA	Pea aphid	<i>Acythosiphon pisum</i>
BB	Mexican bean beetle	<i>Epilachna varivestis</i>
AW	Southern armyworm	<i>Prodenia eridania</i>
BW	Boll weevil	<i>Anthonomus grandis</i>
HF	House fly	<i>Musca domestica</i>
GR	German cockroach	<i>Blattella germanica</i>
FB	Confused flour beetle	<i>Tribolium confusum</i>
GW	Granary weevil	<i>Sitophilus granarius</i>
BCB	Black carpet beetle	<i>Attagenus piceus</i>
Nema	Northern root-knot nematode	<i>Meloidogyne hapla</i>

A test solution containing 600 p.p.m. was made by dissolving the test compound in a solvent (acetone:methanol, 1:1), adding surfactant and then water to give an acetone:methanol:H₂O system of 10:10:80. A 1:1 mixture of an alkylarylpolyether-alcohol (sold under the trademark Triton X-155) and a modified phthalic glycerol alkyd resin (sold under the trademarked name of Triton B-1956) was utilized at the equivalent of 1 ounce per 100 gal. of test solution as a surfactant. For the nematode test a 1200 p.p.m. test solution was used.

For the mite test, infested bean (*Phaseolus limateanus*) leaf discs (1.25 inches in diameter) containing about 50 mites and for green peach aphid tests, infested broccoli (*Brassica oleracea italica*) leaves or portions thereof containing about 50 aphids were placed in a Petri dish lid on a moistened piece of cotton. The leaves were then sprayed with the test solution using a rotating turntable. They were held for 24 hours and then the percent kill was determined.

For the pea aphid test, broad bean (*Vicia faba*) plants pruned to 2 leaves were sprayed manually to run off and allowed to dry. These were placed horizontally in plastic boxes (5 x 7.5 x 3.5 inches) and infested with 50-100 aphids of mixed ages. The boxes were covered with lids containing screened ventilation holes. After 48 hours the percent kill was determined.

For the bean beetle and armyworm test, detached bean leaves on a piece of moistened filter paper were sprayed as above for the mite test in similar containers and allowed to dry. One leaf was transferred to an unsprayed dish also

containing moistened filter paper and infested with 10 third instar Mexican bean beetle larvae. The leaf remaining in the sprayed dish was infested with 10 third instar southern armyworm larvae. The dishes were covered. After holding for 48 hours the percent kill was obtained.

For the boll weevil, hours fly and cockroach tests, half pint glass canning jars with a screened top were used. Food was supplied for the boll weevil (apple) and for the house fly (sugar water). The test insects consisted of 10 adult boll weevils, 20 adult house flies and 10 last instar nymphs for the cockroach. The jars containing the insects were sprayed using the turntable. The percent kill of boll weevil was determined 48 hours after application. In the house fly test a percent knockdown was determined 1 hour after application, the percent kill after 24 hours. Roach kill was determined after 24 hours.

For the flour beetle and granary weevil tests, one-third pint squat glass dishes were sprayed and allowed to dry. There were then introduced about 20 adults of each species into each dish which was then covered. Percent kills were observed after 48 hours.

For the carpet beetle test a 2" square swatch of wool felt (AATCC moth test cloth) conditioned with 1 ml. of acetone was impregnated via pipette with 1 ml. of the test solution and allowed to dry. The cloth was placed in a Petri dish, infested with 10 6-7 month larvae and covered. This was held for about 3 weeks and the percent feeding determined in comparison with untreated fabric held under similar circumstances.

For the nematode test, soil was homogeneously inoculated with a macerated blend of tomato roots heavily knotted with the root-knot nematode. Ten ml. of the test solution was added to 200 ml. of the inoculated soil in a 16 oz. jar to give a concentration by volume of about 60 p.p.m. The jar was then shaken to insure thorough mixing and kept capped for 72 hours. The soil was then placed into a 3" plastic plant pot and allowed to air for about 24 hours after which time 3 cucumber (*Cucumis sativus*) seeds were planted. About twenty-three days thereafter, the cucumber plants were removed from the soil and the root systems examined for the presence of knots. A total of 30 knots is considered as no control (—) and less than that as a measure of control (+).

Table V gives the results of the above biological evaluations.

TABLE V

Insecticidal and Miticidal Data, Percent Control, etc., at 600 p.p.m.

*A value is sometimes given as dead aphid/total aphids

NOTE.—NT=not tested; KD=knockdown.

Ovicidal and larvacidal tests were conducted on representative compounds of this invention.

For mite tests involving the two-spotted mite ova and larvae, bean leaf sections containing about 100 eggs were placed on moistened cotton in a Petri dish and sprayed on the turntable with the 600 p.p.m. test solution described above. These were held for 6 days and examined under the microscope. Unhatched eggs and dead and live larvae were counted and the percent ovicidal and the percent larvacidal activity were determined.

For tests on house fly larvae, two layers of 4.25 cm. filter papers were placed in small Petri dishes, were sprayed on the turntable with a 600 p.p.m. solution of the test compound and were air dried. About 100 eggs of the house fly in about 1 ml. of water were pipetted onto the filter paper and the dishes covered. These were held for 24 hours and examined under the microscope. The percent kill values for larvae were determined.

A second technique for determining house fly larvacidal activity involved incorporation of a test solution into a standard fly media to attain specified concentrations on a weight basis, usually 2 p.p.m. About 100 house fly eggs

were pipetted into a jar containing 50 g. of moistened treated media in an 8 oz. jar. The jars were covered with cheese cloth, held for 5 days and the percent control relative to untreated checks determined.

For tests involving the southern corn rootworm (*Diabrotica undecimpunctata howardi*) ova and larvae, the same technique as described above for house fly larvae by the turntable method was used. The holding period was 6 days. Unhatched eggs and dead and live larvae were counted under the microscope and the percent ovicidal and the percent larvacidal activity were determined.

Mosquito (*Culex spp.*) larvae tests were obtained as follows. Approximately 25 6-day old larvae were introduced into one-third pint squat dishes containing 100 ml. of water which previously had been treated with a test solution of selected compounds so as to give a 1 p.p.m. concentration. Twenty-four hours later the percent kill was determined.

Table VI gives the results of these ovicidal and larvacidal tests.

^a Two-spotted mite.^b Corn rootworm.^c House fly.

NOTE.—NT=not tested; + =affected but not quite moribund; —=data not possible, all eggs destroyed.

Tests designed to determine systemic activity of representative compounds of this invention were conducted. These were soil drench assays.

In one such test involving the two-spotted mite (TSM), a bean seedling consisting of two primary leaves planted in a 3" diameter plastic pot containing 200 ml. of a 50:50 soil-sand mixture was used. The pot was placed in a Petri dish lid and a 10 ml. volume of the test solution containing 600 p.p.m. of the test compound was pipetted onto the soil to give a 30 p.p.m. concentration in the soil. Twenty-four hours later each leaf was infested with bean leaf sections containing about 50 adult female mites. The plant was then held for 48 hours and the percent kill determined via microscopic examination.

A similar test using the green peach aphid (GPA) was conducted except that a broccoli plant consisting of 3-5 leaves was used instead of the bean plant. The percent kill was determined based upon the population present on the plant foliage. An untreated plant would generally have more than 100 aphids per plant. In some instances a toxic material may induce affected aphids to drop from the

plant so that a low population would be observed after the 48 hours holding period. In such cases dead and total aphids on the plant were reported.

A similar test was conducted using the pea aphid (PA) as the test insect. The plant used was a broad bean plant pruned to two leaves. The plant was held in a plastic box and infested by brushing approximately 100 aphids into the box. The percent kill was determined 48 hours later.

Similar systemic tests were also conducted using Mexican bean beetle (BB) and armyworm (AW) as the test insects. The same type of bean plant as used in the mite test above was used for these. After the 24-hour translocation period, the plant was infested with 10 third instar larvae of either the bean beetle or the armyworm, and then held for 72 hours after which the percent kill was determined.

Similar tests were conducted on the mite and insects except that the translocation period prior to infestation was seven days.

Table VII gives the results of the above-described systemic tests for representative examples.

* 300 p.p.m. solution = 15 p.p.m. soil.

b 150 p.p.m. solution = 7.5 p.p.m. soil.

c 75 p.p.m. solution = 3.8 p.p.m. soil.

d 38 p.p.m. solution = 1.9 p.p.m. soil.

* A value is sometimes given as dead aphids/total aphids.

NOTE.—NT = not tested.

Residual studies were made to determine the stability of representative phosphorylthio acrylamides on sprayed foliage or inert surfaces. Such test plants or inert surfaces appropriate to the organism involved were sprayed with the test solution containing 1200 or 600 p.p.m. of the phosphorylthio acrylamide. The plants were then maintained under proper growing conditions for 7 days and for 14 days after which they were infested with the test organism. The sprayed inert surfaces were stored a similar period of time after which they were infested with the appropriate test organism.

For the two-spotted mite test, a bean plant was used and infested from a parent colony so that about 50 mites were placed on each bean leaf. Percent kills were determined 48 hours thereafter.

For the green peach aphid test, a broccoli plant was used and infested from a parent colony with 50–100 aphids. Percent kills were determined 48 hours thereafter.

For the pea aphid test, a broad bean plant was used and this was infested with 50–100 aphids. Percent kills were determined 48 hours thereafter.

For the bean beetle and armyworm tests, bean plants were used. Prior to infestation the bean plants were severed from the roots and the stems immersed in narrow-necked 2 oz. bottles using cotton plugs when necessary to fill in a void between the stem and the neck. For each test 20 third instar larvae of the bean beetle or the armyworm were used. Percent kills were determined 72 hours thereafter.

For the boll weevil, house fly, cockroach, flour beetle and granary weevil tests the same procedures as used in the initial tests described above for Table V were used except that the open jars or dishes were sprayed followed by an ageing period of 7 to 14 days before introduction of the insects and covering with screened lids. Percent kills were determined 48 hours thereafter.

45 Table VIII gives the results on these residual studies on representative compounds of this invention.

* 1,200 p.p.m.

* A value is sometimes given as dead aphids/total aphids.

NOTE.—NT=not tested.

Representative compounds of this invention were found to give good to excellent control of the adult female chicken mite (*Dermanyssus gallinae*). In this test individual Petri dishes were sprayed with the test compound using solutions containing 300, 75, 20, 5, 1.2 or 0.3 p.p.m. and allowed to dry. Approximately 25 to 40 engorged mites, predominantly female, were introduced into each dish. The dishes were held for 48 hours at which time the percent mortality was determined by counting the dead and moribund mites. The following Table IX gives the lowest level of spray concentration which gave a 90-100% mortality. For many of the compounds oviposition has been found to be adversely affected.

TABLE IX.—CHICKEN MITE DATA

Representative compounds of this invention were tested on the chicken body louse (*Menacanthus stramineus*). In this test eight week old White Leghorn cockerels were exposed to a colony of the lice three weeks prior to the test period. At the start of the test a subjective count of the lice infestation was made on each bird by two separate counts in five locations, namely the vent, back, neck, breast and under the wings. The birds were then sprayed with the test compound at three dosage levels (1000, 125 and 15 p.p.m.), using two birds for each treatment level, and allowed to dry. The birds were then held in individual cages for two weeks, then a louse count was made in the same manner as described above and a percent control determined. Table X gives the results.

TABLE X.—CHICKEN BODY LOUSE DATA

The 3-dialkylphosphorylthio- and 3-dialkoxythionophosphorylthio-acrylamides, methacrylamides and related structures of this invention possess general utility as arthropodicides, in particular against members of the class *Arachroidea*, which includes the order *Acarina*, as represented by mites and ticks, and *Insecta*, the insects. Compounds of this invention also have utility as nematocides. Such utilities enable protection of plants and animals, including man, from the ravages of harmful and/or annoying pests or disease organisms which they may carry. Application of said compounds may be made directly to the loci of those pests to be controlled or to the loci to be protected. For example, food, fiber, forage, forest, and ornamental crops and stored products thereof would represent plant protection loci. Treatment with compounds of this invention of domestic animals, man and their immediate environs similarly constitute representative loci for protection against various annoying ectoparasitic or endoparasitic *Acarina* (*Acar*) and *Insecta*. Accordingly compounds of the present invention provide utility as the essential active ingredient of pesticidal compositions suitable for agricultural and sanitary purposes.

For use as pesticides the compounds of this invention may be used as solutions in organic solvents or formulations. For example they may be formulated as wettable powders, emulsifiable concentrates, dusts, granular formulations or flowable emulsifiable concentrates. In such formulations the phosphorylthio acrylamides are extended with an agronomically acceptable liquid or solid carrier and, when desired, suitable surfactants are likewise incorporated. Surfactants commonly used in the art may be found in the John W. McCutcheon, Inc. publication "Detergents and Emulsifiers 1969 Annual."

The phosphorylthio acrylamides may be taken up on or mixed with a finely particled solid carrier, as for example clays, inorganic silicates, carbonates, and silicas. Organic carriers may also be employed. Dust concentrates are

23

commonly made wherein phosphorylthio acrylamides are present in the range of 20 to 80%. For ultimate applications, these concentrates are normally extended with additional solid to give an active ingredient content of from about 1 to 20%. Granular formulations are made using a granular or pelletized form of carrier, such as granular clays, vermiculite, charcoal or corn cobs, and may contain the active ingredient in from 1 to 25% by weight.

Wettable powder formulations are made by incorporating the compounds of this invention in an inert, finely divided solid carrier along with a surfactant which may be one or more emulsifying, wetting, dispersing or spreading agents or blend of these. The phosphorylthio acrylamides are usually present in the range of 10 to 80% by weight and surfactants in from 0.5 to 10% by weight.

One convenient method for preparing a solid formulation is to impregnate the phosphorylthio acrylamide toxicant onto the solid carrier by means of a volatile solvent, such as acetone. In this manner, adjuvants, such as activators, adhesives, plant nutrients, synergists and various surfactants may also be incorporated.

Emulsifiable concentrate formulations may be prepared by dissolving the phosphorylthio acrylamides of this invention in an agronomically acceptable organic solvent and adding a solvent-soluble emulsifying agent. Suitable solvents are usually water-immiscible and may be found in the hydrocarbon, chlorinated hydrocarbon, ketone, ester, alcohol and amide classes of organic solvents. Mixtures of solvents are commonly employed. The surfactants useful as emulsifying agents may constitute about 0.5 to 10% by weight of emulsifiable concentrate and may be anionic, cationic or non-ionic in character. The concentration of the active ingredients may vary from 10 to 80%, preferably in the range of 25 to 50%.

For use as biocidal agents, these compounds should be applied in an effective amount sufficient to exert the desired biocidal activity by techniques well known in the art. Usually, this will involve the application of the phosphorylthio acrylamides to the loci to be protected or eradicated in an effective amount when incorporated in an agronomically acceptable carrier. However, in certain situations it may be desirable and advantageous to apply the compounds directly onto the loci to be protected or eradicated without the benefit of any substantial amount or carrier. This is a particularly effective method when the physical nature of the toxicants is such as to permit what is known as "low-volume" application, that is, when the compounds are in liquid form or substantially soluble in higher boiling solvents.

The application rate will, of course, vary depending upon the purposes for such application, the phosphorylthio acrylamides being utilized, the frequency of dissemination and the like.

Many of the above formulations can be utilized on animals and birds for the control of animal parasites.

For use as insecticides and miticides, dilute sprays may be applied at concentrations of 0.001 to 20 pounds of the active phosphorylthio acrylamide ingredient per 100 gallons of spray. They are usually applied at 0.01 to 5 pounds per 100 gallons and preferably at 0.03 to 1 pound per 100 gallons. In more concentrated sprays, the active ingredient is increased by a factor of 2 to 12. With dilute sprays, applications are usually made to the plants until run-off is achieved, whereas with more concentrated or low-volume sprays the materials are applied as mists.

For use as a nematocide or as a soil or systemic insecticide, the phosphorylthio acrylamides may be applied as a solid formulation, preferably a granular formula-

24

tion, by broadcasting, by side-dressing, by soil incorporation or by seed treatment. The application rate may amount to from 1 to 50 pounds per acre. For soil incorporation the compounds of this invention may be mixed with the soil at a rate of 2 to 100 p.p.m.

The compounds of this invention may be utilized as the sole biocidal agents or they may be employed in conjunction with other bactericides, fungicides, herbicides, insecticides, miticides and comparable pesticides.

We claim:

1. An insecticidal, miticidal and nematocidal composition comprising (1) a carrier and (2) as the active ingredient from 10 to 80% of a compound of the formula

wherein

R^9 and R^{10} are individually methyl or ethyl,
 R^{11} is hydrogen or methyl, and

R^{12} is

- (a) alkyl of 1 to 5 carbon atoms, or
- (b) the $-\text{C}(\text{O})\text{R}^8$ group wherein R^8 is
  - (1) hydrogen,
  - (2) alkyl of 1 to 5 carbon atoms,
  - (3) alkyl of 1 to 5 carbon atoms substituted with halogen, thiocyanato, alkoxy of 1 to 5 carbon atoms, alkylthio of 1 to 5 carbon atoms,
  - (4) C_1 to C_5 alkoxy carbonyl, thiolacetyl, benzyloxy, benzylthio, phenyl, phenoxy, or phenylthio,
  - (5) alkenyl of 2 to 5 carbon atoms,
  - (6) alkenyl of 2 to 5 carbon atoms substituted with C_1 to C_5 alkoxy carbonyl,
  - (7) C_1 to C_5 alkoxy carbonyl, or
  - (8) phenyl.

2. The composition of claim 1 wherein the compound is 3-dimethoxyphosphorylthio-N-ethylacrylamide.

3. The composition of claim 1 wherein the compound is 3-dimethoxyphosphorylthio-N-formylacrylamide.

4. The composition of claim 1 wherein the compound is 3-ethoxy(methoxy)phosphorylthio-N-formyl acrylamide.

5. The composition of claim 1 wherein the compound is 3-dimethoxyphosphorylthio-N-chloroacetylacrylamide.

6. The composition of claim 1 where the said compound is 3-dimethoxyphosphorylthio-2-methyl-N-ethylacrylamide.

7. A method for controlling insects, mites and nematodes which comprises applying to said insects, mites and nematodes or to the loci to be protected therefrom an insecticidally, miticidally and nematocidally effective amount of the composition of claim 1.
